UNITED STATES PATENT OFFICE

THOMAS E. McCUTCHEON, OF WASHINGTON, DISTRICT OF COLUMBIA

TITLE

Application filed August 9, 1932. Serial No. 628,077.

This invention relates to tiles and more particularly to that class of tiles especially adapted to be embedded in the walls of buildings or other structures at the floor line there-
5 of to form a protecting border or splash-board around the rooms of the building and commonly known as base tiles.

Heretofore, in building construction, the tiles used for the splash boards of the rooms 10 of a building have generally been provided with smooth or plain outer faces with the result that the workmen in laying the plastic sub-structure and surface material of the floor have found it necessary to employ gage 15 strips positioned next to the tiles in order to determine the proper thickness and level of the sub-surface material and the thickness and level of the floor material so that there will be no irregularities in the finished floor.

20 These gage strips are not only costly and expensive to install but often become lost or misplaced and consequently work on the floor must be interrupted until they are found and placed in proper position.

25 The primary object of the present invention is to obviate these difficulties and to provide a tile having means forming an integral part thereof for accurately determining the proper height and level of both the sub-structure and 30 surface material of a floor without the employment of gage strips and similar auxiliary devices.

A further object of the invention is to provide a tile having its outer face rabbeted 35 to form upper and lower shoulders offset with respect to each other and defining straight edges one of which determines the proper height and level of the sub-structure of the floor and the other the height and level of 40 the surface material.

A further object is to provide a tile the upper straight edge of which may be used as a gage or marker against which preformed surface material, such as rubber, cork or 45 composition flooring may be pressed whereby to form a guide line or indentation thereon and thus facilitate cutting said material to accurately fit within the rabbet of the tile.

A still further object of the invention is 50 generally to improve this class of devices so

as to increase their utility, durability and efficiency.

In the accompanying drawing forming a part of this specification:

Figure 1 is a perspective view of a base 55 tile constructed in accordance with the present invention.

Figure 2 is a transverse sectional view of a portion of a building showing the manner 60 of using the tile.

Figure 3 is a similar view showing a border tile used in connection with the base tile.

Similar numerals of reference indicate corresponding parts in all the figures of the 65 drawing.

The improved base tile forming the subject matter of the present invention comprises an upright body portion 5 formed of terra cotta or other suitable material and which may have its exposed face glazed or provided 70 with a dull finish, as desired. The back of the tile is provided with transverse anchoring grooves 6 for the reception of the material constituting the wall 7 of the building whereby the tile may be firmly anchored thereto. 75 The lower end of the tile is deflected laterally to form an angular extension 8 which is embedded in the plastic sub-structure 9 constituting a portion of the floor. The outer end of the extension 8 forms a vertical abutment 80 10 against which the sub-structure 9 bears so as to firmly anchor the lower end of the tile in proper position. The upper edge of the extension 8 at the exposed face of the tile is transversely rabbeted at 11 to form shoulders 85 12 and 13 offset with respect to each other and defining upper and lower straight edges 14 and 15. The rabbet 11 forms a seat for the surface material 16 of the floor while the upper straight edge 14 serves as a gage 90 to determine the proper height and level of said surface material. When the surface material is preformed and made of rubber, cork, or a composition of matter, and laid in strips on the sub-structure 9, the upper straight 95 edge 14 acts as a gage or marker against which the surface material may be pressed to form an indentation therein and thus enable the strips of surface material to be accurately cut to fit the rabbet. The lower 100

straight edge 15 also forms a gage to enable the workman to properly determine the exact height or surface level of the sub-structure material so that the upper surface of the 5 sub-structure 9 will present a smooth, even surface for the reception of the surface material. It will thus be seen that the surface material abuts against the upper shoulder 12 while the plastic sub-structure bears 10 against the lower shoulder and as said shoulders are offset with respect to each other, a stepped joint will be provided which will securely hold the tile in place. The upper face of the tile at the extension 8 is preferably 15 curved or dished inwardly, as indicated at 16, and merges into the upper straight edge 14 so as not to offer any surface obstructions at the junction of the tile with the floor.

In use, the tile is laid into the wall 7 at 20 the floor line of the room of a building, after which the plastic sub-structure 9 is laid upon the foundation 17 and the workman trowels or otherwise finishes the upper surface of the sub-structure on a level with the straight edge 25 15. If the surface material is to be formed of cement, terrazzo or like material, said surface material is positioned on the sub-structure with the surface material entering the rabbet, as best shown in Figure 2 of the drawing, and the upper surface of the surface material troweled off or otherwise finished so as to be in horizontal alinement with the upper straight edge 14. When, however, the 30 surface material is in the form of strips of rubber, cork, or other composition of matter, said surface material is positioned on the sub-structure and then pressed downwardly against the upper straight edge 14, which will 35 form an indentation therein or a mark thereon which acts as a gage and thus permits the workman to readily cut or sever the strip of material to accurately fit the rabbet. It will 40 thus be seen that the rabbeted edge of the extension 8 of the tile not only forms a seat 45 for the surface material of the floor but the upper and lower edges of the rabbet constitute straight edges for the workman to work to and thus enables the workman to determine the exact height and level of both the 50 sub-structure and surface material without the employment of gages or similar auxiliary devices now in use for this purpose. As the rabbet forms an integral part of the tile it necessarily follows that when said tile is positioned in a wall, the means for accurately determining the height and surface level of 55 both the sub-structure and surface material is always at hand, which is quite a desideratum, thereby avoiding interruption of the 60 work often happens when gages are used and

said gages become lost or misplaced during the construction of the building.

In Figure 3 of the drawing, there is illustrated a modified form of the invention in which border blocks 18 are used in conjunction with the tiles. In this form of the device, the base tiles 5 are of ordinary construction while the border blocks or tiles 18 are laid horizontally into the sub-structure 9 in advance of the base tiles 5 and have their outer edges rabbeted at 19 similarly to the base tile shown in Figure 1 of the drawing, which rabbeted edges perform the same function in the same manner as the rabbets in the extension of the base tiles.

It will, of course, be understood that the tiles may be made in different sizes and shapes and constructed of any material found suitable or desirable for the purpose, without departing from the spirit of the invention.

Having thus described the invention, what I claim is:

1. As a new article of manufacture, a base tile comprising an upright body having its lower portion provided with a downwardly inclined lateral extension the end of which is formed with a transverse rabbet extending the entire width of the tile and opening through the top and front face of said extension to provide an open seat for floor surfacing material and an abutment at the end of the extension for engagement with a floor sub-structure, the walls of the rabbet being disposed at substantially right angles to each other and defining upper and lower straight edges, one of which indicates the level of the floor surfacing material and the other the level of the floor substructure.

2. In building construction, the combination with a wall and floor including a sub-structure and surfacing material, of a base tile comprising an upright body having its rear face provided with anchoring members embedded in the wall and its lower end provided with a lateral extension embedded in the substructure, said extension being provided with a transverse rabbet opening through the top and front face of said extension and forming an open seat for the surfacing material and an abutment at the end of the extension against which the substructure bears, the walls of the rabbet being disposed at an angle to each other and defining upper and lower straight edges disposed in alinement with the upper surface of the surfacing material and substructure respectively, and the exposed face of the body gradually merging into the upper surface of said extension.

In testimony whereof I affix my signature.

THOMAS E. McCUTCHEON. [L. S.] 125
